GEORGE P. WALKER, GEORGE B. CORAM, JOHN DENNIS, AND C. H.
ROBBINS, ALL OF SAME PLACE.

SWITCH FOR STORE-TRACKS.

SPECIFICATION forming part of Letters Patent No. 278,657, dated May 29, 1883.

Application filed July 13, 1882. (No model.)

To all whom it may concern:

Be it known that I, JOHN C. CORAM, of the city of Lowell, county of Middlesex, and State of Massachusetts, have invented a new and useful Improvement in Switches for Store-Tracks, of which the following is a specification.

My invention relates to tracks used in stores to convey rolling objects from place to place, in which objects money or messages may be transmitted; and its objects are to provide a switch adapted to direct different sets of balls or rolling objects to different tracks from a single track, being actuated by the balls themselves as they pass down the main track, and to provide a mechanism whereby the switch shall be locked in position while the balls are passing over it, and to cause them to automatically return the switch, when thrown into position for use with the branch line, into connection with the main line after use. I accomplish these objects by the mechanism illustrated in the accompanying drawings, in which—

Figure 1 is a plan view of a track provided with a switch of my construction. Fig. 2 is an end view, looking toward the switch down the main line. Fig. 3 is a detail showing the locking device and reversing-lever as attached to the inside of the inner rail of the branch, such rail being removed from the other portions of the track.

A is the main line of the track, consisting of the outside rail, a, and inside rail, a².

B is the branch track, consisting of the rails b and b², this latter being a continuation of the inside rail, a², of the main line above the switch.

C is the frog of the switch. This frog is pivoted by a horizontal pintle, upon which it rocks or oscillates, to the point of juncture of the rails b and a² at one end, and by means of a yoke, d, is pivoted, by a like horizontal pivot, centrally to a cross-bar, e, such curvature being given the yoke that whichever rail of the frog is in line with the track-rails the other will be thrown so low that it will not be

in the way of balls or conveyers rolling down the line.

c is the outer rail of the frog C.

c² is the inner rail. When the frog C is tilted so that the rail c² is raised to the level of the rail a², it shuts off the switch and forms a continuous main track, because the rail c is then depressed so low as to be entirely out of the way beneath the main track. When the frog C is rolled or rocked on its pintles so as to bring the rail c up to the level of the rail a, the rail c² will be correspondingly depressed and out of the way, and c will form a connecting-rail between a and b, closing up the main track and shunting a rolling ball upon the side track. It is of course understood that the pintle at the junction of rails a² and b keeps that end of the rails c c² substantially on a level with a² b, while the pintle at the end d of the frog is at all times at one-half the distance below the track to which the rails c or c² can be depressed by the oscillation of the frog.

c² is a catch-pin inserted into the inner rail, by means of which the switch is locked when in line with the branch track B.

D is bail supporting lever f. This lever is provided with a cam which is in contact with the catch-lever g, which is pivoted at g², and provided with the hook g³ at its lower end, which engages in a notch in the arm h, which is attached to the frog. The arm h is weighted, as shown, so that whenever the hook g³ is disengaged from the arm h the gravity of the weight will throw up the rail c, so as to bring it level with the rails a and b, and cause any object rolling down the line A to be carried onto the branch B.

J is the reversing-lever, through the instrumentality of which the frog, after having shunted a ball from the main line, is returned to its original position. This lever is pivoted at 1 to the inner side of rail b², and stands in the position indicated in Fig. 3 when the frog has moved so as to bring its rail c uppermost and in line with rail b. In this position its end farthest removed from the frog projects above the level of the track, in a position to be

acted on and depressed by the shunted ball, this end of the lever being flattened on top to facilitate the passage of the ball over it. The other arm of lever *J* is of such length as to extend to the immediate neighborhood of rail *c*² of the frog, and is provided at its end with a projecting lug, *j*. Adjoining the depressed end of the lever is a freely-swinging catch, *k*, which by gravity tends to assume a position in which its beveled lower end, *k'*, will overhang the end of the lever. This catch *k* is provided on its side next to the frog with a lateral shoulder or projection, *k*², situated thereon at a point above the bevel *k'*. Fastened to rail *c*² of the frog is a pin, *c*³, which projects laterally therefrom, and is of such length that it will extend under the locking shoulder or projection *k*². When it occupies this position it will extend across above the lug *j* of the lever, as indicated. The effect of this arrangement is as follows: Supposing the frog to be in its normal or main-line position, if there be sent over the main track a ball which is too small to operate lever *f*—whose cam part (shown in side elevation in Fig. 4) bears against locking-lever *g*—the switch will remain unaffected, and the ball will continue on the main track. If, however, the ball be of sufficient size to strike lever *f* and turn it on its axis, the cam part of this lever will bear down upon the upper end of lever *g*, moving it to the position shown by dotted lines in Fig. 2, and thus removing the catch *g*³ from the weighted arm *h*. The latter, on its release, at once falls to the position shown in dotted lines, thereby turning the frog on its pivot in a direction to depress rail *c*² and to raise rail *c* into line with the rail *b* of the side track. As the rail *c*² descends, its laterally-projecting pin bears down upon the lug *j* of the lever *J*, (which we will suppose had been raised by the passage of the last previously shunted ball over the side track,) and thus depresses this end of lever *J*, which, in its descent, pushes back before it the freely-swinging catch *k*. As soon as the end of the lever descends below the beveled lower part, *k'*, of the catch, the catch swings forward by gravity until the beveled part *k'* overhangs the end of the lever, in which position the shoulder or projection *k*² will overhang the pin *c*³, thus locking the switch or frog in its shunting position. At this time the flattened end of the lever *J* is raised above the level of the track.

The operation just described takes place instantly as soon as the weighted arm *h* is unlocked. The ball, after passing lever *f*, is consequently shunted upon the side track, *B*, over which it passes. In so doing it rides over and depresses the flattened end of lever *J*, and the other end of the lever of course rises. In this movement it first, by coming in contact with the beveled edge *k'*, pushes back the catch *k* far enough to move the shoulder *k*² back from over the cross-pin *c*³, and then its lug *j* comes up against and lifts the pin *c*³ against the stress of weighted arm *h*, and thus returns the frog to its original or main-line position, in which it is again locked by the re-engagement of the arm *h* with catch *g*³.

In case there are a number of switches at various points on the main track, I make the switch-levers *f* of different lengths, setting them in regular order, so that the first reached shall be the farthest removed from the track, and thence gradually decreasing the elevation at each succeeding switch. Thus the largest balls only will be shunted at the first switch, and so on to the last switch, which will be reached by the smallest balls only.

What I claim as new and of my invention is—

1. The combination of the main line *A* and branch *B* with the shifting frog *C*, actuated by a shifting-lever projecting over the track, with which the carrier moving down the main line comes into contact, substantially as described.

2. The combination of a main track and branch track with a frog provided with a rail held in alignment with the main track by a catch-lever and a balance-weight, with such balance-weight adapted, when such catch-lever is operated, to shift the alignment of the rails to the branch by the gravity of the weight, substantially as described.

3. The combination of a main and branch lines of track, and a frog whose rails can be aligned with either the main or branch rails, with a lever located beyond the switch upon the branch track, adapted to automatically return the frog-rail to alignment with the main line each time a rolling object passes over the branch, substantially as described.
